UNITED STATES PATENT OFFICE.

PHILIP H. BEVIER, OF BROOKLYN, NEW YORK, ASSIGNOR TO NATIONAL FIRE PROOFING COMPANY, OF PITTSBURGH, PENNSYLVANIA, A CORPORATION OF PENNSYLVANIA.

BUILDING TILE.

Application filed April 4, 1925. Serial No. 20,741.

The present invention relates to building tiles, and more particularly to building tiles of the so-called double shell type.

Building tiles are usually formed with 5 parallel side walls connected by a plurality of transverse webs extending at right angles to the side walls and forming therewith square cells. All square cell tiles, when laid on the side, have a tendency to collapse when 10 the clay is unburned, and even when burned. Moreover, such tiles are fragile to manufacture and the breakage in shipping is very great.

While the present invention, in its broader 15 aspect, is applicable to square cell tiles generally, it is particularly directed to overcoming the above objectionable features in the so-called double shell tiles.

In the drawings:

20 Figure 1 is a perspective view of a double shell tile embodying a preferred form of my invention, and

Figure 2 is a horizontal sectional view of the tile shown in Figure 1. 25 Referring to the illustrated embodiment of the invention, the tile comprises parallel cellular side walls, each of said side walls embodying closely spaced parallel longitudinally extending shells or webs 2 and 30 3 spaced apart by transverse connecting webs 4, thus forming double shell side walls, which are continuous or uninterrupted throughout their length and width except 35 for the usual mortar retaining ribs. The side walls are connected adjacent the ends of 40 the tile by transverse webs 5 extending at right angles to the side walls. Heretofore, it has been customary to also connect the side walls by intermediate transverse webs 45 50 parallel to the end webs 5. As already stated, this construction was liable to collapse in the green state and even after burning, since the transverse webs offered little resistance to relative longitudinal movement between the side walls when the tile was 55 laid on its side when being handled or shipped. Moreover, the tile so constructed was fragile and therefore liable to be easily broken.

50 I overcome these difficulties without adding appreciably to either the weight or the cost of the tile by substituting for the usual intermediate web 6, two V-shaped webs 8

having their vertices directed towards each other and connected by a short longitudinal- 55 ly extending web 9. These webs 8 and 9 form, in effect, two oppositely inclined diagonal webs which cross each other and are integrally connected by the common web portion 9, thereby forming an approximate- 60 ly X-shaped web connecting the cellular side walls of the tile adjacent its center and bracing the side walls of the tile against relative longitudinal movement in either di- 65 recton. The V-shaped webs 8 brace each other through the connecting web portion 9 whereby there is no tendency of these webs to collapse due to the load on the tile.

I have shown the tile provided with short 70 interior diagonal webs 10 at the corners of the tile connecting the end webs 5 with the cellular side walls. These webs may be omitted, if desired, thereby reducing the weight of the tile, but they have a useful function in addition to bracing the tile, 75 namely, to secure the side walls firmly to the end webs 5 where there is a tendency for the tile to break when subjected to the shearing effect of unequal expansion when ex- 80 posed to fire.

The tile can be broken into two half sec- 85 tions on the line *a*—*a* of Figure 2, which bisects the web 9, or can be broken along the line *b*—*b* of Figure 2 to get a two-thirds piece.

While I have shown and described the preferred embodiment of my invention it will be understood that the invention is not limited to its illustrated embodiment, but that it may be otherwise embodied within 90 the scope of the appended claims without departing from the spirit of the invention.

I claim:

1. A tile having parallel side walls and transverse vertical webs connecting the parallel side walls, a short longitudinal web centrally located between the walls and diagonal webs connecting opposite ends of the short web with the side walls intermediate the ends thereof and at a substantial distance from the vertical webs. 95

2. A tile having parallel side walls and transverse vertical webs connecting the parallel side walls, a short longitudinal web centrally located between the walls, diagonal 100 webs connecting opposite ends of the short

105

web with the side walls intermediate the ends thereof, and diagonal webs in the corners of the tiles connecting the side walls and the vertical webs.

- 5 3. A tile having parallel side walls which are double, with webs to hold the double walls apart, transverse end walls connecting the parallel side walls, a short longitudinal web centrally located between the side walls, and diagonal webs connecting opposite ends of the longitudinal web with the double side walls intermediate the ends thereof and at a substantial distance from the end walls.
- 10 4. A tile having parallel double uninterrupted side walls, transverse end walls connecting the side walls, and a substantially X form of bracing web between the side walls intermediate the ends thereof.

- 15 5. A tile having parallel double uninterrupted side walls, transverse end walls connecting the side walls, and a substantially X form of bracing web between the side walls intermediate the ends thereof, said double side walls having spacing webs there-
20 in at substantially the outer ends of the X-formed bracing webs.

6. A hollow building tile adapted to be used with the openings therethrough vertical, having vertical side walls which are
25 connected adjacent their ends by transverse vertical end walls, and oppositely directed diagonal bracing webs connecting the vertical side walls intermediate their length and

at a substantial distance from the ends of the tile, said diagonal webs joining each other at approximately the center of the block.

7. A hollow building tile adapted to be used with the openings therethrough vertical, having vertical side walls which are connected adjacent their ends by transverse vertical end walls, and oppositely directed diagonal bracing webs connecting the vertical side walls intermediate their ends, said diagonal webs joining each other at approximately the center of the block, the side walls being substantially thicker than the other walls and webs of the block.

8. A tile having parallel side walls and transverse vertical end webs connecting the side walls, said end webs being set inwardly from the ends of the tile so as to provide an external channel at each end thereof, the end webs being connected to the side walls through diagonal branches, whereby support is provided for the projecting end portions of the side walls, a short longitudinally extending web centrally located between the walls, and diagonal webs connecting opposite ends of the short web with the respective side walls intermediate the end webs of the tile.

In testimony whereof I have hereunto set my hand:

PHILIP H. BEVIER.
